UNITED STATES PATENT OFFICE.

LOUIS C. HILLER, OF MERIDEN, CONNECTICUT, ASSIGNOR TO THE MERIDEN SILVER PLATE COMPANY, OF SAME PLACE.

DESIGN FOR A SPOON OR FORK HANDLE.

SPECIFICATION forming part of Design No. 13,136, dated August 8, 1882.

Application filed July 12, 1882. Term of patent 14 years.

To all whom it may concern:

Be it known that I, LOUIS C. HILLER, of Meriden, in the county of New Haven and State of Connecticut, have invented a new Design for Spoon and Fork Handle; and I do hereby declare the following, when taken in connection with accompanying drawing and the letters of reference marked thereon, to be a full, clear, and exact description of the same, and which said drawing constitutes part of this specification, and represents a face view. This invention relates to a design for the ornamentation of the handles of spoons, forks, and like articles of table service; and it consists in the ornamentation on the face of the handle, as shown in the accompanying illustration. In outline the handle gradually expands from the boss *a* to the tip, where it terminates in an elliptical arch shaped across the face of the handle, and at the base of the tip portion is a narrow reeded band, *b*. From the boss *a* is a panel, terminating in lancet shape about two-thirds the distance between the boss and the point *b*, and above this lancet-shaped panel is an inverted lancet-shaped panel, the panels formed by beads, which appear to cross each other at the intersection of their points, and at the points is a rose ornament. The surface of the lower panel has upon it the representation of a thistle, the upper panel left plain. The spandrels—that is, the surface outside the points of the two panels—are orna-

mented by scroll-work tracery, all as shown in the accompanying illustration.

The ornamentation of the spandrels and the lower panel may be omitted or other ornamentation introduced. I therefore do not limit this design to the particular ornamentation of the panel.

The band *b* may also be omitted or other ornament substituted therefor.

What I claim is—

1. The herein-described design for spoon and fork handle, consisting of the lower lancet-shaped panel and the upper inverted lancet-shaped panel, as shown in the accompanying illustration.

2. The herein-described design for spoon and fork handle, consisting of the lower lancet-shaped panel and the upper inverted lancet-shaped panel, the lower panel having upon its surface the representation of a thistle, as shown in the accompanying illustration.

3. The herein-described design for spoon and fork handle, consisting of the lower lancet-shaped panel and the upper inverted lancet-shaped panel, with the transverse reeded band *b* above the upper panel at the base of the tip, as shown in the accompanying illustration.

LOUIS C. HILLER.
